BOXING GLOVE

Edward Joseph Cartier, Toronto, Ontario, Canada,
assignor of one-half to William Conley, To-
ronto, Ontario, Canada

Application May 24, 1939, Serial No. 275,527
In Canada June 6, 1938

6 Claims. (Cl. 2—18)

This invention relates to boxing gloves and it consists in the constructions, arrangements and combinations herein described and claimed.

It is the cardinal object of the invention to provide a construction of glove body which may be moulded from rubber or compositions having similar characteristics, permitting fabrication of a glove which is devoid of facing or covering material, thereby eliminating stitches, seams and like raised parts.

It is also an object of the invention to provide a new and novel construction in the main body of the glove, reducing weight and increasing the resilience of the body.

A further object of the invention is to provide a novel construction of hand envelope complementary to the main body of the glove for permanent securement thereto.

Additional objects, advantages and features of invention will be apparent from the following description, considered in conjunction with the accompanying drawing, wherein,

Figure 1 is a plan view of the main body portion of a glove constructed in accordance with my invention,

Figure 2 is a longitudinal sectional view through a glove constructed in accordance with the invention,

Figure 3 is a plan view of the envelope member.

Figure 4 is a longitudinal sectional view on the line 4—4 of Figure 3.

Figure 5 is an end elevation of the main body shown in Figure 1 viewed in the direction of the wrist portion,

Figure 6 is a cross section on the line 6—6 of Figure 1.

Figure 7 is a side elevation of the interior hand grip employed in the hand envelope.

Figure 8 is a similar view of the exterior hand grip.

Figure 9 is a fragmentary cross section through the hand envelope at the lacing portion thereof.

Figure 10 is a partial end elevation of the hand envelope illustrating the wrist portions.

Attention is first invited to Figure 2 of the drawing wherein there is shown a boxing glove 10 consisting of a main body 11 and a hand envelope 12.

The main body 11 is formed from rubber, preferably sponge rubber, and includes an integral one-half wrist portion 13 and a thumb stall 14 which is open upon one side. The body 11 may have an exterior contour quite similar to that of the ordinary boxing glove, but the interior of the body is provided with a plurality of openings 15

spaced longitudinally of the body, each opening being elongated in the direction of the exterior contour of the glove and of a width stopping short of the longitudinal edges of the body 11. 5 It should be noted that by elongating the openings 15 in the direction of the exterior contour of the body 11, the openings adjacent the tip of the glove and adjacent the wrist portion are of lesser length than the openings in the medial and adjacent portions of the glove body. Such construction permits ready clenching of the glove, since the wall portion 16 between the openings may be readily flexed and maintaining the outer surface of the glove smooth.

10 The body 11 may be formed in a mold constructed to shape the main body 11, the openings 15, walls 16, the half wrist section 13 and thumb stall portion 14, and in addition the interior longitudinal medial portion 11a of the body should 15 and adjacent portions of the glove body. Such construction permits ready clenching of the glove, since the wall portion 16 between the openings may be readily flexed and maintaining the outer surface of the glove smooth.

15 The body 11 may be formed in a mold constructed to shape the main body 11, the openings 15, walls 16, the half wrist section 13 and thumb stall portion 14, and in addition the interior longitudinal medial portion 11a of the body should 20 and adjacent portions of the glove body. Such construction permits ready clenching of the glove, since the wall portion 16 between the openings may be readily flexed and maintaining the outer surface of the glove smooth.

20 The body 11 may be formed in a mold constructed to shape the main body 11, the openings 15, walls 16, the half wrist section 13 and thumb stall portion 14, and in addition the interior longitudinal medial portion 11a of the body should 25 and adjacent portions of the glove body. Such construction permits ready clenching of the glove, since the wall portion 16 between the openings may be readily flexed and maintaining the outer surface of the glove smooth.

25 The body 11 may be formed in a mold constructed to shape the main body 11, the openings 15, walls 16, the half wrist section 13 and thumb stall portion 14, and in addition the interior longitudinal medial portion 11a of the body should 30 and adjacent portions of the glove body. Such construction permits ready clenching of the glove, since the wall portion 16 between the openings may be readily flexed and maintaining the outer surface of the glove smooth.

30 The body 11 may be formed in a mold constructed to shape the main body 11, the openings 15, walls 16, the half wrist section 13 and thumb stall portion 14, and in addition the interior longitudinal medial portion 11a of the body should 35 and adjacent portions of the glove body. Such construction permits ready clenching of the glove, since the wall portion 16 between the openings may be readily flexed and maintaining the outer surface of the glove smooth.

35 The body 11 may be formed in a mold constructed to shape the main body 11, the openings 15, walls 16, the half wrist section 13 and thumb stall portion 14, and in addition the interior longitudinal medial portion 11a of the body should 40 and adjacent portions of the glove body. Such construction permits ready clenching of the glove, since the wall portion 16 between the openings may be readily flexed and maintaining the outer surface of the glove smooth.

40 The body 11 may be formed in a mold constructed to shape the main body 11, the openings 15, walls 16, the half wrist section 13 and thumb stall portion 14, and in addition the interior longitudinal medial portion 11a of the body should 45 and adjacent portions of the glove body. Such construction permits ready clenching of the glove, since the wall portion 16 between the openings may be readily flexed and maintaining the outer surface of the glove smooth.

45 The body 11 may be formed in a mold constructed to shape the main body 11, the openings 15, walls 16, the half wrist section 13 and thumb stall portion 14, and in addition the interior longitudinal medial portion 11a of the body should 50 and adjacent portions of the glove body. Such construction permits ready clenching of the glove, since the wall portion 16 between the openings may be readily flexed and maintaining the outer surface of the glove smooth.

50 The body 11 may be formed in a mold constructed to shape the main body 11, the openings 15, walls 16, the half wrist section 13 and thumb stall portion 14, and in addition the interior longitudinal medial portion 11a of the body should 55 and adjacent portions of the glove body. Such construction permits ready clenching of the glove, since the wall portion 16 between the openings may be readily flexed and maintaining the outer surface of the glove smooth.

The slot 20 is provided at its longitudinal sides with a lacing strip 24 adhesively or otherwise secured to the wall 25 of the envelope and at the lower portion of the slot 20 and a reinforcing 55 and lace protecting strip 24' is similarly secured to the wall 25, the strip extending upwardly into contacting engagement with respective portions of the reinforcing members 22.

Centrally of the wall 25 of the envelope, upon both sides thereof, hand grip members 26 are se-

cured materially assisting in clenching of the glove for use as well as affording support to the hand of the user.

By interrupting the reinforcements 22 of the hand envelope 18 it is possible to readily separate the members 22 laterally for insertion of a hand within the envelope, and since the reinforcements are of rubber the inherent resilience thereof will return these members to normal position above the lacing strips 24.

While I have specifically described and shown my construction of glove this is by way of illustration only and I consider as my own all such modifications in structure as fairly fall within the scope of the appended claims.

I claim:

1. A boxing glove comprising a main body member of rubber of substantial transverse thickness, a wrist portion integrally formed with the body member, said body member having a recess upon one side and extended through the wrist portion, a thumb portion, integrally formed with the body member, and a hand envelope complementary to the recess and fixed therein.

2. A boxing glove comprising a main body member of rubber of substantial transverse thickness, a wrist portion integrally formed with the body member, said body member having a recess upon one side and extended through the wrist portion, a thumb portion integrally formed with the main body and having an open side, said main body member having a plurality of openings spaced longitudinally intermediate the length thereof; a hand envelope including a thumb portion and a wrist portion, the envelope being positioned within the recess with the thumb portion engaged within the thumb portion of the main body, the wrist portion of the hand envelope being complementary to the wrist portion of the main body, and adhesive means between contacting portions of the envelope and the main body member.

3. The structure of claim 2 in which the hand envelope includes a slot extended from the open end inwardly a distance, lacing strips fixed to the sides of the slot, and reinforcing strips fixed to the hand envelope partly overlying the lacing strips.

4. A boxing glove comprising a main body

member of rubber of substantial transverse thickness, a wrist portion integrally formed with the body member, said body member having a recess upon one side and extended through the wrist portion, a thumb portion integrally formed with the main body and having an open side, said main body having a plurality of transverse openings spaced longitudinally intermediate the length thereof; a hand envelope including a thumb portion and a wrist portion, the envelope being positioned within the recess with the thumb portion engaged within the thumb portion of the main body, the wrist portion of the hand envelope being complementary to the wrist portion of the main body and adhesive means between contacting portions of the envelope and the main body member.

5. A boxing glove comprising a main body member of rubber of substantial transverse thickness, a wrist portion integrally formed with the body member, said body member having a recess upon one side and extended through the wrist portion, a thumb portion integrally formed with the main body and having an open side, said main body having a plurality of transverse openings spaced longitudinally intermediate the length thereof; the openings being elongated in the direction of the exterior contour of the main body, the transverse length of the openings being such as to stop inwardly of the longitudinal edges of the main body member, a hand envelope including a thumb portion and a wrist portion, the envelope being positioned within the recess with the thumb portion engaged within the thumb portion of the main body, the wrist portion of the hand envelope being complementary to the wrist portion of the main body and adhesive means between contacting portions of the envelope and the main body member.

6. The structure of claim 5 in which the hand envelope comprises a slot extended from the open end inwardly a distance, lacing strips fixed to the sides of the slot, reinforcing strips fixed to the palm portion of the envelope and partly overlying the lacing strips, and opposed hand grip members fixed to the palm portion of the hand envelope inwardly of the closed end thereof.

EDWARD JOSEPH CARTIER.
